UNITED STATES PATENT OFFICE.

EDWARD POSSON, OF CHICAGO, ILLINOIS, ASSIGNOR TO CAMEL COMPANY, OF CHICAGO, ILLINOIS, A CORPORATION OF MAINE.

ROOF-FRAME FOR CARS.

1,025,996.

Specification of Letters Patent.

Patented May 14, 1912.

Original application filed March 29, 1910, Serial No. 552,131. Divided and this application filed March 7, 1911. Serial No. 612,797.

To all whom it may concern:

Be it known that I, EDWARD POSSON, a citizen of the United States, residing at Chicago, in the county of Cook and State 5 of Illinois, have invented certain new and useful Improvements in Roof-Frames for Cars, of which the following is a specification.

My invention relates to improvements in 10 car roof frames and more particularly to a carline and suitable means for attaching the same to the rest of the roof frame structure.

This application is a division of my co-pending application Serial No. 552,131, filed 15 March 29, 1910, for a car roof construction.

The principal object of my invention is to provide an improved car roof frame of simple, strong and inexpensive construction.

Another object is to furnish, in connection 20 with the said roof frame, a well braced carline, the construction of which requires little work either by machine or by hand.

One of the objects is to produce a carline comprising a rolled bar of standard form 25 for a body in connection with a pair of well braced cast metal forked ends having thoroughly strong and rigid means for fastening the said parts together and ample means for attaching the carline to other parts of 30 the roof frame.

While my roof frame is in some respects similar to the frame disclosed in my Patent No. 955,544 of April 19, 1910, I aim to greatly improve the carline therein de- 35 scribed.

These and other objects will be more fully set forth and made apparent in the following specification and claims in connection with the accompanying drawings showing a 40 preferred embodiment.

Figure 1 is a plan view of a portion of my car roof with a part of the said roof broken away to show more clearly the framework and the relation of my improvements there- 45 to. Fig. 2 is a side elevation of same with portions broken away. Fig. 3 is a trans- 50 verse vertical section across the roof on the line 3—3 of Fig. 1. Fig. 4 is a longitudi- 55 nal vertical section of a portion of the roof taken on the line 4—4 of Figs. 1 and 3. Fig. 5 is a detail in section showing the rela- 60 tion of the end of a carline to one of the side plates. Fig. 6 is a perspective view of my 65 improved carline assembled complete and

ready for installation in a car roof frame. 55 Fig. 7 is a cross section of the same on the line 7—7 of Fig. 6. Fig. 8 is a sectional detail showing a modification of attachment of my carline to the side plates. Fig. 9 is a sectional view crosswise of the car showing 60 my improved carline attached to a steel side plate, which in this case is a channel bar. Fig. 10 is a sectional view showing my im- 65 proved form of carline attached to a steel side plate which has the form of an angle bar. Fig. 11 is an underneath view of the end of one of my carlines showing its con- 70 nection to a steel side plate. Fig. 12 is a perspective view showing a carline end simi- 75 lar to that shown in Fig. 11, but without connection to a side plate. This view shows clearly how the horizontal flanges are cut away from the extreme ends so as to enable the vertical flanges to fit closely to the side plate. Fig. 13 is a cross section showing a 80 modification in which an I-beam is used for the middle portion of the beam, the section being at a point where the said I-beam is riveted to the cast metal forked ends. Fig. 14 is a cross section of another modification 85 in which two angle bars are used for the middle portion of said beam, the bars being placed together edge to edge and the section being at the point where the angle bars are riveted to the forked end portion. 85

In all drawings like reference numerals apply to like parts.

In the accompanying drawings I have preferred to show my improved carline in connection with a roof framework which 90 supports metal roof plates beneath the usual wooden roof.

The framework of the car roof comprises the usual side plates 16, placed longitudinally of the car, end plates 17 placed transversely of the car, the purlins 18 and the ridge beam 19, the latter members lying longitudinally of the car. Transversely ar- 95 ranged directly beneath the ridge beam and purlins are the carlines 20. 100

Each of the carlines comprises a body portion 20' and forked end portions 21. An important feature of these carlines consists in the making of the body portions of rolled material while the forked ends may be made 105 of cast material. In the forked end por- 100 tions 21 I prefer to use material known as "malleable iron." The forked end portions

are secured to the body portion 20' by suitable rivets 22 or other substantial means. The body portion 20' is securely attached to the ridge beam 19 by the bolts 32, and to the purlins 18 by the bolts 23.

The forked end portions 21 are spread widely apart, preferably at about 90°, and terminate in ends 24, which are bent still farther apart until they lie in substantially the same line. These end portions 24 bear against the side plates 16. The outwardly extending flanges 25 of these end portions are embedded in suitable grooves in the inner side of the side plates. These carline ends 24 are firmly secured to the side plates by the yoke bolts 26, as shown clearly in Fig. 1. This method of embedding a portion of the end of the carline in the side plate is intended to be used in connection with wooden side plates only. The method of attaching the carlines to steel side plates is hereinafter described.

The body portion 20 of the carline is preferably of channel form, having a web 27 and downwardly extending flanges 28. The web portion 27 is attached to the frame members 18 and 19 by suitable bolts. The forked end portions 21 each comprises a flanged body 29 having downwardly extending flanges 30 through which the rivets pass that attach it to the main channel and two divergent arms that extend outwardly and are attached to the side plates. The said body portion is given such a size and form as to cause it to fit snugly around the end of the body portion 25, as shown most clearly in Figs. 4 and 7.

The body portion of the carline may also be made of an I-beam 33, shown in cross section in Fig. 13. In this case the forked end portion must have a special form at the point where it engages the bar, as shown at 53 in Fig. 13.

Another convenient form, if preferred, comprises two angle bars placed edge to edge for a body portion, as shown at 54 in Fig. 14, in which a cross section is represented. In this case a regular form of a forked end piece may be used, such as already described and as shown at 55 in Fig. 14.

The purlin 18 may be recessed, as shown at 31 on Fig. 4, to receive the body portion 29 of the forked ends. The carline may be attached to the ridge beam 19 by the bolts 32, the spacing block 45 being provided to preserve the same spacing at the center of the car as exists at points where the purlins 18 are placed. The carline is given a bent form, which permits it to conform to the general slope of the roof. There is preferably a short portion 34 which lies horizontally and meets the sloping end portions 35 at the bends 36 where the outer portions incline downward. In the form of

car roof which I have preferred to show in connection with my improvements, the usual fascia board 37 is used. The yoke bolts 26 pass through the fascia board and are secured in position by the washer plates 56 and the nuts 38.

The corrugated metal plate 39 lies immediately above the side plates 16 and the purlin 18, and is embedded in the ridge beam 19 at its inner edges. Its inclined lateral edges are embedded in the sub-carlines 43. Immediately above this corrugated metal plate are placed the sub-purlins 40, upon which are placed the roof boards 41. The roof boards are also spaced from the corrugated plates 39 by the supplementary ridge members 42 and the supplementary side plates 44, the latter being located directly above the main side plates 16, as shown in Fig. 3. The sub-carlines 43 serve for a number of purposes comprising means to support the sides of the corrugated plates 39, also to space the purlins 18 from the sub-purlins 40, likewise they serve to separate plates 16 and 44 and also to separate the ridge members 42 and 45. The diagonal corner braces 46 are attached to the side plate in similar manner to the forked end 21, and also to the end members or plates 17.

It will be understood that my improved carlines are adapted for all kinds of roofs, although I have illustrated them in connection with a roof which is made up of a metal roof within the usual wooden roof.

My improved carlines are adapted to any form of roof structure in which said roof must be supported by members arranged transversely of the car body, and in which said members are subjected to diagonal stresses. The forked end portions of my improved carlines very readily transmit the said diagonal stresses from the side plates to the purlins and to the inner portions of the framework.

I have thus far described my improved carline in connection with wooden side plates only, as shown at 16 in Fig. 3. In order to permit its use in connection with metal plates I have provided suitable means, as disclosed in Figs. 9, 10, 11 and 12. In Fig. 9 I have shown a sectional detail in which a channel bar 47 is used as a side plate. The end 48 of one of the forks is modified sufficiently by cutting off a portion of a horizontal flange to permit the vertical flange to lie close against the web of the said channel bar, as shown at 49. The detail of this construction is more clearly shown in perspective view in Fig. 12 and also in Fig. 11. The end of the vertical flange 50, which remains after drilling off the end of the horizontal flange, may be riveted to the web of the channel bar, as shown in Figs. 9 and 11. In Fig. 10 I have

further illustrated the use of my carline in connection with metal side plates. In this case an angle bar 51 is used as a side plate against which the forked ends of the carline 5 are riveted or otherwise attached, substantially as shown in Fig. 11. In Fig. 8 I have shown a transverse sectional detail in which the end of the carline is attached to a wooden side plate by means of plain bolts 52 in place of the yoke bolts hereto referred to. Otherwise the carline is attached to the wooden plates, substantially as described in the first part of my specification, the horizontal flange 25 being placed in a suitable 10 groove cut in the side of the wooden plate.

I do not in this application claim broadly a car roof construction comprising metallic carlines having an arched form sloping downwardly from the central part of the 20 car toward the sides thereof, the end parts of the carlines being bifurcated and the bifurcated portions diverging toward the car sides, although I disclose herein a specific embodiment of such generic invention, 25 inasmuch as such generic invention is broadly claimed in my Reissue Patent No. 13,297, granted October 3, 1911, the application for which was copending with the original application of which this present 30 application is a division.

Having thus described my invention, what I claim and desire to secure by Letters Patent is:

1. In roof construction for railway cars, 35 a carline comprising a central member and end members secured to the ends of the central member, each of said end members being divided longitudinally and spread diagonally apart.
2. In roof construction for railway cars, 40 a carline comprising a central member and end members secured to the ends of the central member, each of said end members being divided longitudinally and spaced 45 diagonally apart and terminating in extremities spread still farther apart so as to lie in the same plane.
3. In a roof construction for railway cars, 50 a carline comprising a central member having side flanges and flanged end members overlapping and secured to the ends of the central member, the flanges of the overlapped portions of said members being in close contact, each of said end members be-

ing divided longitudinally and spaced 55 diagonally apart.

4. In a car roof framework, the combination with side plates, of carlines each comprising a central member and end members secured to the ends of the central member, 60 the end members of each carline being divided longitudinally and spread diagonally apart and secured to the side plates, purlins, a rigid beam supported by the carlines, and a roof resting on said purlins. 65

5. In a car roof framework, the combination with side walls, of metal carlines extending completely across the car and secured to and supported upon said side walls, 70 each of said carlines comprising a central arched member and bifurcated end members secured to the ends of the central member, the bifurcated parts of the end members diverging toward the car sides to which they are secured, whereby the arches formed by the carlines are braced against tilting longitudinally of the car and whereby the entire structure forms an approximately horizontal truss. 75

6. In a car roof framework, the combination with a set of carlines, each comprising a central member and end members secured to the ends of the central member, each of said end members being bifurcated and the bifurcated parts spaced diagonally apart, of 80 purlins intersecting the carlines at the joints between the central and end members thereof, and means for securing said purlins to both the central and respective end members of the carlines. 85

7. In a car roof framework, the combination with a set of carlines, each comprising a central flanged member and flanged end members overlapping and secured to the ends of the central member, each of said end members being bifurcated and the bifurcated parts spread diagonally apart, of purlins intersecting the carlines at the overlapped portions of the central and end members thereof, and means for securing said purlins to 95 the overlapped portions of the central and respective end members of the carlines. 100

In testimony whereof, I have subscribed my name.

EDWARD POSSON.
